PHOTOGRAPHIC FLASHGUN OR SIMILAR ARTICLE

James E. Hunter, Jr., Norwood, Mass., assignor to Polaroid Corporation, Cambridge, Mass., a corporation of Delaware

Application January 19, 1955, Serial No. 34,058

Term of patent 14 years

(Cl. D61—1)

FIG. 1

Fig. 2 is a side elevational view thereof; and

Fig. 3 is a rear elevational view thereof.

The essential features of my design reside in the parts shown in full lines.

I claim:

The ornamental design for a photographic flashgun or similar article, substantially as shown and described.
